UNITED STATES PATENT OFFICE

2,678,725

APPARATUS FOR CLASSIFYING ARTICLES
BY COLOR

Woodrow R. Jacobson, Schenectady, N. Y., assignor to General Electric Company, a corporation of New York

Application December 29, 1949, Serial No. 135,682

6 Claims. (Cl. 209—111)

1

This invention relates to an improved method and apparatus for classifying and sorting articles by color.

In the manufacture of articles which are commonly sold from a package containing a plurality of the articles, such as cigars, it is often desirable to sort the articles by color before placing them in packages, so that all articles placed in the same package have the same appearance. This makes the package more attractive, and promotes sales.

An object of this invention is to provide automatic means for quickly and economically sorting articles by color.

Color classification comprises two factors: chromaticity and brightness. Chromaticity refers to the redness or blueness of the articles, and brightness refers to its lightness or darkness. This invention provides for the sorting of articles according to a "dual classification" based upon chromaticity and brightness.

Other objects and advantages will appear as the description proceeds. The features of the invention which are believed to be novel and patentable are pointed out in the claims which form a part of this specification.

For a better understanding of the invention, reference is made in the following description to the accompanying drawing, in which Fig. 1 is a schematic view, partly in section, of apparatus embodying principles of this invention; Fig. 2 is a plan view of a rotary shutter used in the Fig. 1 apparatus; and Fig. 3 is a spectrophotometric curve of a cigar.

Referring now to Fig. 1, an electric lamp 1, a collimating lens 2, and a pair of beam-forming slits 3 provide two beams of light represented by broken lines in the drawing. The intensities of these two beams are modulated in phase opposition by a rotary shutter 4 driven by an electric motor 5 through shaft 6 and gears 7.

Referring now to Fig. 2, which is a plan view of rotary shutter 4, the broken circles 8 and 9 represent cross sections of the two beams of light. Shutter 4 may comprise three blades, as shown, and may be rotated at a speed of 1800 R. P. M., for example. The shutter intensity modulates each of the light beams at a frequency of 90 cycles per second. The two beams are modulated in phase-opposition to each other; that is, when one beam is completely cut off by the shutter, the other beam is completely transmitted.

Again referring to Fig. 1, one of the light beams passes through a lightly silvered mirror 10. The silverying of mirror 10 is sufficiently light that only a part of the light is reflected by the mirror, while a part is transmitted through the mirror.

The two light beams next pass through an attenuator for adjusting the relative intensities of the two beams. This attenuator may be of the

2

type which comprises a large disc of polarizing material 11 and two smaller discs of polarizing material 12 and 13. The small discs 12 and 13 are placed in respective light beams with their respective axes of polarization perpendicular to each other. For example, disc 12 may be positioned for maximum transmission of light which is polarized in a direction perpendicular to the plane of the drawing, and disc 13 may be positioned for maximum transmission of light which is polarized in a direction parallel to the plane of the drawing.

The large polarizing disc 11 is positioned in both beams. When the polarizing axis of disc 11 is parallel to the polarizing axis of disc 12, the maximum amount of light is transmitted in the left-hand beam, and the minimum amount in the right-hand beam. When disc 11 is turned 90°, so that its polarizing axis is parallel to that of disc 13, the maximum amount of light is transmitted in the right-hand beam, and the minimum amount in the left-hand beam. Adjustment of disc 11 to any intermediate position provides a corresponding intermediate adjustment of the relative intensities of the two light beams. An adjustment knob 14 and gears 15 may be provided for adjusting the position of disc 11.

The two beams next pass through two color filters 16 and 17, respectively, to provide two beams of different colors. Filter 16 may be blue and filter 17 may be red, for example. Then the beams pass through prismatic lenses 18 and 19, respectively, and are thereby directed to an article to be sorted, 20, which may be a cigar.

Light reflected by the cigar is collected by an integrating sphere 21. This is a substantially spherical enclosure having a white diffusing inner surface, so that the entire volume within the sphere is at substantially the same brightness. The brightness within the sphere depends upon the total amount of light reflected by cigar 20. Operation of the integrating sphere is not substantially affected by the fact that portions of the "sphere" may be flat, as illustrated, to facilitate the attachment of other apparatus.

Part of the reflected light collected by the integrating sphere passes through an opening 22 to first photoelectric means, which may comprise a phototube 23, a source of direct voltage 24, and a load resistor 25. This first photoelectric means is responsive to both colors of light reflected by the cigar 20; and since these colors alternate in time, any difference in average intensity of the two colors of reflected light produces an alternating component in electric current conducted by phototube 23. This, in turn, produces an alternating current through resistor 25, which current is related in amplitude and phase to the magnitude and sign of the intensity difference between the two colors of reflected light.

On the other side of the integrating sphere, part of the reflected light passes through an opening 26 to second photoelectric means, which may comprise a color filter 27, a phototube 28, a source of direct voltage 29, and a load resistor 30. Filter 27 preferably is the same color as filter 16, and has substantially zero transmission in the region of the spectrum where filter 17 transmits. Hence it transmits only blue light. Therefore, the second photoelectric means is responsive to one color only of the reflected light.

The light which is reflected by mirror 10 passes through an attenuator comprising a fixed polarizing disc 31 and a rotatable polarizing disc 32. The amount of light transmitted through this attenuator is adjustable by adjusting the position of disc 32 to bring the polarizing axes of the two discs nearer to or farther from parallelism. An adjusting knob 33 and gears 34 are provided for adjusting the position of disc 32.

The light which passes through disc 32 is transmitted through a light-conducting tube 35, which may be made of Lucite, or may be a system of mirrors or reflecting prisms, for example. The light emerges from tube 35 at end 36, is then reflected by a mirror 37 to phototube 28. Thus a reference value of light from the right-hand beam is transmitted to phototube 28; while the amount of light from the left-hand beam which reaches this phototube depends upon the amount of such light reflected by cigar 20. Since the two beams are intensity-modulated in phase opposition, an alternating current is provided through resistor 30 which depends in magnitude and phase upon the average intensity of light of a single color reflected by cigar 20.

As is hereinafter more fully explained, the value of alternating current through resistor 25 corresponds to the chromaticity of the cigar, and the value of alternating current through resistor 30 corresponds to the brightness of the cigar. These currents produce alternating voltages across resistors 25 and 30, which are amplified by amplifiers 38 and 39, respectively, and are then applied through transformers 40 and 41 to phase-sensitive rectifier bridges 42 and 43 comprising a part of a classifying means hereinafter described.

Connected to motor 5, and rotated thereby, is a small alternator 44 which generates alternating current having the same frequency as the intensity-modulation of the light beams provided by shutter 4: 90 cycles per second, for example. This alternating current is transmitted through transformer 45 to phase-sensitive rectifier bridges 42 and 43. Preferably, the voltage across the secondary of transformer 45 is considerably larger than the maximum voltage to be obtained across the secondary of transformer 40 or the secondary of transformer 41.

The secondaries of transformers 40, 41, and 45 are each provided with a center tap. The output voltage of rectifier bridge 42 is obtained between the secondary center tap of transformer 40 and the secondary center tap of transformer 45. When no current is applied to the primary of transformer 40, this output voltage is zero. When a current is applied to transformer 40 which is in-phase with the current applied to the primary of transformer 45, the output voltage is positive; and when the two currents are out-of-phase, the output voltage is negative. In a similar manner, the output voltage of rectifier bridge 43 is obtained between the secondary center tap of transformer 41 and the secondary center tap of transformer 45. Values of these two output voltages 75

indicate the color classification of the cigar, or other article, and control sorting equipment through electronic switches likewise comprising part of the aforementioned classifying means.

5 The classifying means also includes a first electronic switch which may comprise vacuum tubes 46, 47, 48, and 49, having anodes connected in series with energizing coils of relays 50, 51, 52, and 53, respectively. The vacuum tubes 46-48 have control electrodes connected together and to the secondary center-tap of transformer 40; and have cathodes connected to different points on a voltage divider 54 connected across a direct voltage source 55, as shown; so that the cathodes are maintained at different potentials, and the tubes have different values of bias voltage between their respective cathodes and control electrodes.

These bias voltages may have values such that when the output of rectifier bridge 42 is zero, tubes 46 and 47 are conductive and relays 50 and 51 are energized, while tubes 48 and 49 are non-conductive and relays 52 and 53 are de-energized. When rectifier bridge 42 provides a positive output voltage, the negative bias of tubes 48 and 49 is decreased, and at a selected value of such output voltage tube 48 becomes conductive and relay 52 is energized. At a larger value of positive output voltage, tube 49 becomes conductive and relay 53 is energized. At a selected value of negative output voltage from rectifier bridge 42, tube 47 becomes nonconductive and relay 51 is de-energized, and at a larger negative value, tube 46 becomes non-conductive and relay 50 is de-energized. The various states of the relays thus correspond to five chromaticity classifications, and the relays may operate suitable sorting machinery to sort the articles classified into chromaticity groups.

40 The classifying means also further includes a second electronic switch which comprises vacuum tubes 56, 57, 58, and 59, having anodes connected in series with energizing coils of relays 60, 61, 62, and 63, respectively. The control electrodes of tubes 56-59 are connected together and to the secondary center-tap of transformer 41, and their cathodes are connected to different points on a voltage divider 64 connected across a direct voltage supply 65. Operation of the second electronic switch is similar to that of the first switch, except that the relays of the second switch may operate sorting machinery to sort the articles into five groups of different brightness. Thus, under the combined control of the two electronic switches, the articles are sorted into 25 different groups corresponding to the 25 possible combinations of five classes of brightness and five classes of chromaticity. It will be appreciated that other numbers of groups may be used. For example, in sorting cigars only nine groups corresponding to three classes of chromaticity and three classes of brightness are generally satisfactory. A change in the number of groups requires only a change in the number of elements in the electronic switches.

Referring now to Fig. 3, curve 66 represents a typical spectrophotometric curve of a cigar, which shows the percentage of light of various wavelengths reflected by the cigar. Such a curve may be made by a spectrophotometer. Dotted curves 67 and 68 represent the transmission characteristics of filters 16 and 17, respectively. The transmission characteristic of filter 27 is preferably the same as that of filter 16, and hence is also represented by curve 67.

The chromaticity of the cigar is represented by the average slope of curve 66. To measure this average slope within the visible light region, values near the two ends of the visible spectrum are compared by measuring the difference in the amount of blue light reflected by the cigar and the amount of red light so reflected. This difference may have a certain value for cigars of average chromaticity, which should be sorted into the middle group of the chromaticity classification; and cigars for which the difference in reflection at these two colors is substantially greater or less than this average value should be sorted into other groups.

The selection of the two wavelengths used to determine the chromaticity of an object can best be made by analysis of spectrophotometric curves of representative samples of the objects to be sorted. That is, representative samples of the objects, such as cigars, are sorted according to their appearance to the eye, and spectrophotometric curves are made with a spectrophotometer of each object in the sample. These will be curves similar to curve 66 for cigars. Then by comparison of the curves so obtained with the sorting of the objects by appearance, that portion of the curves is selected which varies in average slope most markedly in correspondence with variations in color apparent to the eye. The best pair of wavelengths to use in sorting are those at respective ends of the portion of the spectrophotometric curves so selected. For example, in color sorting of cigars, best color differentiation can be obtained with color filters having maximum transmission at 500 and 620 millimicrons, respectively, as illustrated by curves 67 and 68; Fig. 3; while in color sorting of lemons, best results are obtained with filters having maximum transmission at 550 and 675 millimicrons, respectively.

The brightness of the cigar is represented by the distance of curve 66 above the horizontal axis. Thus, different brightness values, chromaticity being the same, would be represented by similar curves having a fixed vertical separation from each other. Thus brightness may be determined by measurements made at any one color. In the apparatus described, blue has been selected arbitrarily. A cigar of average brightness is selected to establish the middle group of the brightness classification. Cigars having substantially different brightness values are sorted into other groups.

Referring again to Fig. 1, the apparatus preferably is adjusted with a cigar having average chromaticity and average brightness. Polarizing disc 11 is rotated to adjust the relative intensities of the two light beams until the cigar of average chromaticity produces no alternating current through resistor 25, and hence zero output from phase-sensitive rectifier bridge 42. Disc 32 is rotated to adjust the amount of light transmitted from the right-hand beam to phototube 28 until the cigar of average brightness produces no alternating current through resistor 30, and hence zero output of phase-sensitive rectifier bridge 43. Cigars having substantially these chromaticity and brightness values will then always be sorted into the center group. The limits of each group into which the cigars are sorted can be adjusted by adjusting the taps on voltage dividers 54 and 54, to which the cathodes of the various vacuum tubes are connected. This adjusts the bias voltage on these tubes, and adjusts the values of grid voltage, at which the respective tubes become nonconductive or conductive.

Since a two-beam comparison system is used for both the chromaticity and the brightness classifications, calibration of the apparatus is very stable, and is not affected by moderate variations in brightness of lamps 4. However, a substantial change in the color temperature of light emitted by lamp 4 will affect the calibrations. Therefore, it may be desirable to operate the lamp from a regulated power supply. However, small variations in current through the lamp filament are not objectionable, since the color of the light emitted is affected much less than the brightness by such variations.

It will be appreciated that this invention is not limited to the sorting of cigars, but is equally applicable to the sorting of other articles by color; and may also be used for classification or color monitoring of products which must be maintained at uniform color, for rejecting color-defective articles, or for controlling a manufacturing process to prevent color deviations of the product.

Having described the principles of this invention and the best mode in which I have contemplated applying those principles, I wish it to be understood that the examples described are illustrative only, and that other means may be employed without departing from the true scope of the invention.

30. What I claim as new and desire to secure by Letters Patent of the United States is:

1. Apparatus for classifying articles by color, comprising means to provide two light beams of different colors, means to direct such beams to an article to be classified, means for modulating the intensities of such beams in phase opposition, an integrating sphere to collect substantially all light reflected by such article, photoelectric means responsive to both colors of such collected light, whereby an alternating electric signal is obtained which is related to the chromaticity of such article, and photoelectric means responsive to only one color of such collected light, whereby an electric signal is obtained which is related to the brightness of such article.

2. Apparatus for classifying articles by color, comprising means to provide two light beams of different colors, means to direct such beams to an article to be classified, means for modulating the intensities of such beams in phase opposition, means for adjusting the relative intensities of such beams, an integrating sphere to collect substantially all light reflected by such article, first photoelectric means responsive to both colors of such collected light, whereby an alternating electric current is obtained which is related to the chromaticity of such article, second photoelectric means responsive to only one color of such collected light, means to direct a reference value of light to said second photoelectric means, such reference light being intensity modulated in phase opposition to the reflected light to which said second photoelectric means responds, whereby an alternating electric current is obtained which is related to the brightness of such article, and classifying means responsive to each of said photoelectric means for classifying such articles into groups according to chromaticity and brightness classes corresponding to selected values of such electric currents.

3. Apparatus for classifying articles by color, comprising a light source which provides first and second light beams, a shutter for modulating the intensities of such light beams in phase opposition, an attenuator for adjusting the relative in-

tensities of such light beams, color filters positioned in the two beams to transmit different colors in the respective beams, means to direct the two colored light beams to an article to be classified, an integrating sphere to collect substantially all light reflected by such article, first photoelectric means responsive to both colors of such collected light, whereby an alternating electric current is provided which has an amplitude and phase related to the chromaticity of such article, second photoelectric means responsive to such collected light having the color of such first beam only, means to transmit a reference value of intensity-modulated light from such second beam to said second photoelectric means, whereby an alternating electric current is provided which has an amplitude and phase related to the brightness of such article, and classifying means comprising phase-sensitive rectifying means and electronic switches responsive to each of said photoelectric means for classifying such articles into groups according to chromaticity and brightness classes corresponding to selected values of such electric currents.

4. Apparatus for classifying articles by color, comprising a light source which provides first and second light beams, a shutter for modulating the intensities of such light beams in phase opposition, an adjustable attenuator for adjusting the relative intensities of such light beams, said attenuator comprising a rotatable polarizing disk in the path of both beams and two polarizing disks arranged in the paths of respective ones of such beams, said two polarizing disks being oriented with their directions of polarization perpendicular to each other, different color filters positioned in the respective paths of the two beams, so that the beams have different colors after passing through the filters, means to direct the two colored beams to an article to be classified, an integrating sphere arranged to collect substantially all light reflected by such article, first photoelectric means responsive to both colors of such collected light, whereby an alternating electric current is provided which has an amplitude and phase related to the chromaticity of such article, second photoelectric means responsive to such collected light having the color of such first beam only, means including another adjustable attenuator and a light-transmitting tube for transmitting a reference value of intensity-modulated light from such second beam to said second photoelectric means, whereby an alternating electric current is provided which has an amplitude and phase related to the brightness of such article, and classifying means comprising phase-sensitive rectifying means and electronic switches for classifying articles into groups according to chromaticity and brightness classes corresponding to selected values of such electric currents.

5. Apparatus for classifying articles by color, comprising a light source which provides first and second light beams, a shutter for modulating the intensities of such light beams in phase opposition, an attenuator for adjusting the relative intensities of such light beams, color filters positioned in the two beams to transmit different colors in the respective beams, means to direct the two colored light beams to an article to be classified, an integrating sphere to collect light reflected by such article, first photoelectric means responsive to both colors of such reflected light, whereby an alternating electric current is provided which has an amplitude and phase re-

lated to the chromaticity of such article, second photoelectric means responsive to such reflected light having the color of such first beam only, means to transmit a reference value of intensity-modulated light from such second beam to said second photoelectric means, whereby an alternating electric current is provided which has an amplitude and phase related to the brightness of such article, and classifying means comprising first and second phase-sensitive rectifier bridges, first, second and third transformers each having a primary winding and a center-tapped secondary winding, the secondary winding of said first transformer being connected across opposite corners of both of said bridges, the secondary windings of said second and third transformers being connected across the other corners of said first and second bridges respectively, means for energizing the primary winding of said first transformer by an alternating voltage synchronized with said shutter, circuit means for energizing the primary winding of said second transformer by said alternating current which is related to the chromaticity of such article, circuit means for energizing the primary winding of said third transformer by said alternating current which is related to the brightness of such article, a ground connection to the secondary winding center tap of said first transformer, a first plurality of electron discharge devices each having a cathode, a control electrode and an anode, means for maintaining the respective cathodes of said first plurality of discharge devices at different electric potentials with respect to ground, the control electrodes of said first plurality of discharge devices being connected to the secondary winding center tap of said second transformer, a second plurality of electron discharge devices each having a cathode, a control electrode and an anode, means for maintaining the respective cathodes of said second plurality of discharge devices at different electric potentials with respect to ground, the control electrodes of said second plurality of discharge devices being connected to the secondary winding center tap of said third transformer, and a plurality of relays connected to respective anodes of said discharge devices.

6. Apparatus for classifying articles by color comprising means to provide two light beams of different colors, means to direct such beams to an article to be classified, means for modulating the intensities of such beams in phase opposition, photoelectric means responsive to both colors of light reflected by the article for deriving an alternating electric signal related to the chromaticity of the article, additional photoelectric means responsive to only one color of light reflected by the article for deriving an electric signal related to the brightness of the article, and means responsive to electric signals produced by both of said photoelectric means for producing an indication of the color and brightness classification of the article.
